[57] CLAIM

The ornamental design for a chair, as shown and described.

DESCRIPTION

FIG. 1 is a right-front perspective view of a chair showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front view of another embodiment of the chair showing our new design, the sole difference being a higher backrest.

The fragmented cross-hatching shown on the seat and backrest is understood to represent fabric and would be continuous throughout the implied areas.
